UNITED STATES PATENT OFFICE.

JOHN J. MURPHY, OF NORWICH, CONNECTICUT.

COMBINED POLICE NIPPER AND TWISTER.

1,199,100.

Specification of Letters Patent. Patented Sept. 26, 1916.

Application filed December 27, 1915. Serial No. 68,618.

To all whom it may concern:

Be it known that I, JOHN J. MURPHY, a citizen of the United States, residing at Norwich, in the county of New London, in the State of Connecticut, have invented a certain new and useful Improvement in Combined Police Nippers and Twisters, of which the following is a specification, reference being had to the accompanying drawings.

This invention has for its object the improvement of leaders of the type used by police and other officers, for controlling and leading refractory criminals; my purpose being to provide a leader which, while being reasonably humane, may be readily used by the officer with such painful effect on the prisoner's wrist or ankle that the prisoner will be easily controlled.

Heretofore, so-called "nippers" have been used, which may be clasped upon a criminal's wrist as, for example, the nipper patented by me July 20, 1915, under No. 1,147,423, and, in other instances, so-called "twisters," constructed of chain or cord have been used. Said nippers, however, when used under the excitement of an arrest, are likely to be closed so tightly upon the criminal's wrist as to cut and lacerate the flesh, and the said chain or cord twisters, in order to be effective, must be twisted upon themselves several turns, which is, sometimes, neither convenient or possible in the hurry of making an arrest.

My present device is of such construction and operation that it may be instantly closed upon a wrist and used as a nipper or twister, or as both nipper and twister, by a single quick movement of the officer's hand.

My invention is clearly illustrated in the annexed drawings, Figure 1 being a plan view of a combined nipper and twister embodying the improvements, which I have briefly described; the device being shown open and ready for use in this view. Fig. 2 is a similar view showing the said nipper closed for use as a nipper. Fig. 3 is like the Fig. 2 excepting that the device is adjusted to be used as a nipper and twister.

Fig. 4 is an edge view of the device when used as a nipper only, and Fig. 5 is a like view showing the chain twisted, as in Fig. 3. Fig. 6 is a detached view of the handle member. Fig. 7 is a perspective view of that portion of the body member upon which I have mounted a latch and a safety bolt

adapted to coöperate with the said latch, and in Fig. 8 I have shown a cut section on line 8—8 of Fig. 7.

In some respects the device thus illustrated is like that of my said Patent No. 1,147,423, that is to say, it includes a body member 10 having crab-like jaws 11 and 12 hinged thereto, and a handle member 13 with notched stem 14 adapted to slide in the body 10, also a latch 15 adapted to engage the said notched stem for the purpose of latching the body and stem in fixed relation to each other when the device is adjusted to its operative position. The inner end portion of the stem 14, however, is connected by chains 16 and 17 with the hinged jaws 11 and 12, the arrangement of the stem, the chains, and the jaws being such that, when the stem is drawn outward in the body 10, the said jaws will be swung toward each other until their free ends overlap as seen in Fig. 2 of the drawings. In order to lock the device in its closed position, I have provided a latch 15, which is fulcrumed on the frame 10 at 19, the inner or concealed end of the said latch being adapted to engage the notches in the stem 14, as a pawl, and thus to prevent the accidental opening of the nipper jaws when the device is in use; the said latch being retained yieldingly in engagement with the said stem notches by a spring 20. By simply pressing upon the exposed end of the latch, the latch may, however, be readily withdrawn from the stem notches, when the claws 11 and 12 will be automatically opened by means of springs 21—22, as will be understood by reference to Fig. 1 of the drawings. By the same action the chains will draw the stem 14 outward as seen in said Fig. 1. It will now be understood that by drawing the stem outward, in the body 10, the chains will close the jaws 11—12 and that by releasing the said stem from the restraining action of the latch 15, the springs 21—22 will spread the jaws and set the device in its open inoperative position.

It is sometimes desirable to lock the latch 15 in its engaged position in the stem notch, in order that the nipper may not open by accident or by the act of the prisoner, and I have therefore provided for that purpose a safety lock 23 that is slidably mounted on the body 10 and includes a milled thumb-piece section 23^a, by means of which the lock may be slid lengthwise and also a bar

23^b, which, when the safety-lock 23 is slid outward, (that is toward the handle 13), is moved to a position directly under the otherwise free end of latch 15, and thus blocks 5 the said latch and prevents it from being rocked on its fulcrum. When it is desired to unlatch the said latch, it is only necessary to slide the lock 23 forward a distance sufficient to move its block 23^b out from its position under the end of the latch.

10 I will now describe the action of my device as a twister as well as a nipper.

15 The stem 14 is loosely fitted in the body 10 and the notches extend entirely around the said stem thus making it possible to rock, or partially rotate, the stem as well as to slide it lengthwise in said body. The act of thus partially rotating the stem operates to twist the chains and thus to swing the 20 jaws 11—12 toward each other and to cause the said jaws to close tighter upon the wrist of the criminal. By the same movement the chain links are caused to embed themselves in the flesh of the wrist of the criminal, but

not to lacerate the flesh. Thus it becomes 25 possible and easy for the officer to close the nippers onto the wrist of the criminal and, if the criminal becomes refractory, he may be subdued by a partial twist, or rotation, of the handle 13 and the stem 14 with respect to the body member 10.

Having thus described my invention I claim as new and wish to secure by Letters Patent:

1. A combined nipper and twister comprising a nipper body, jaws hinged to said body, a stem slidably and rotatably mounted in said body, and chain connections between said stem and jaws.

2. A combined nipper and twister, comprising a nipper body, jaws hinged to said body, a stem slidably and rotatably mounted in said body, chain connections between said stem and jaws, means for latching said jaws in their closed position, and means for locking the said latch in its operative position.

JOHN J. MURPHY.
